FUEL FEEDING DEVICE FOR INTERNAL COMBUSTION ENGINES

Fritz Egersdörfer, Berlin, Germany

Original application September 4, 1937, Serial No. 162,430. Divided and this application May 18, 1938, Serial No. 208,618. In Germany September 26, 1932

1 Claim. (Cl. 103—2)

This application is derived by division from an application filed by me September 4, 1937, Serial No. 162,430.

My invention relates to improvements in fuel feeding devices for internal combustion engines, and more particularly in fuel feeding devices of the type in which the fuel is injected by means of a pump comprising a pair or pairs of inter-engaging gear wheels rotating within a common casing and having suction and pressure conduits located respectively at opposite sides of the line of engagement of the said gear wheels, the pressure conduit of the said pump being connected with a distributing device taking part in the rotary movement of the said gear wheels and having ports for supplying the fuel to the cylinders of the engine. The object of the improvements is to provide a fuel feeding device of this type which is simple in construction, and which requires little space, and with this object in view my invention consists in providing the ports of the said distributing device respectively in the shaft carrying one of the said gear wheels and in one of the bushings providing bearings for the said shaft.

For the purpose of explaining the invention an example embodying the same has been shown in the accompanying drawings in which the same reference characters have been used in all the views to indicate corresponding parts. In said drawings:

Fig. 1 is a sectional elevation showing the fuel feeding device,

Fig. 2 is a sectional plan view taken on the line 2—2 of Fig. 1, and

Figs. 3 and 4 are sectional elevations taken respectively on the lines 3—3 and 4—4 of Fig. 1.

In the example shown in the figures the feeding device comprises a casing composed of a cylinder 1 and heads 2 and 3, and a pair of inter-engaging gear wheels 4 and 5. The gear wheel 4 is fixed to a driving shaft 6, and the gear wheel 5 is rotatably mounted on a bushing 49 carried by a shaft 7. The driving shaft 6 is rotatably mounted in bushings 8 and 9 fitted within the cylinder 1, and the shaft 7 is mounted in bushings 10 and 11. At opposite sides of the line of intersection of the gear wheels 4 and 5 suction and pressure conduits 12 and 13 are provided in the wall of the cylinder 1, and the suction conduit 12 is connected with a supply of fuel.

The bushing 11 is shorter in length than the bushing 10, and the gear wheel 5 is shiftable within the casing in axial direction for varying the amount of fuel fed by the pump. For thus

shifting the gear wheel 5 in axial direction a lever 31 is provided which is jointed to the shaft 7 and connected with a governor or a hand operated controlling device such as the accelerator. When the shaft 7, the bushings 10 and 11 and the gear wheel 5 are shifted to the right a reduced portion of the length of the gear wheels is operative so that the amount of fuel fed by the gear wheels is reduced.

The shaft 7 is fixed to the bushings 10 and 11 respectively by screw threads 47 and a key 48, and the bushing 49 provides a spacing member for the bushings 10 and 11.

The driving shaft 6 is provided with an axial socket 35 which is connected through a radial bore 36 with a circumferential slot 37 made in the shaft, and the said slot cooperates with radial bores 38 made in the bushing 9 and ending at their inner ends in circumferential slots 55. The said radial bores communicate with bores 39 made in the cylinder 1 and ending in screw threaded sockets 40 adapted to have pipes connected thereto through which the fuel is supplied to the cylinders of the engine. In the head 2 a passage 41 is made which establishes connection between the socket 35 and a socket 42 made in the cylinder 1 and communicating with the pressure conduit 13, a spring pressed valve 44 being provided for preventing back flow of the fuel into the pressure conduit.

The operation of the device is as follows: The fuel supplied by the gear wheels to the pressure conduit 13 flows through the socket 42, and it is delivered therefrom through the bore 36 into the bores 39 and to the pipes connected with the cylinders. The amount of fuel is regulated by shifting the shaft 7, the bushings 10, 11, and the gear wheel 5 to the right and it depends on the lengths of the slots 37 and 55. The lengths of the said slots are such that the fuel is delivered to the successive cylinders during the desired injection period, and so that the slot 37 is temporarily closed as against successive slots 55 when it leaves one slot 55 and before it registers with the next one, so that successive passages 38 are never connected with each other through the slot 37. The excess of fuel escapes from the passage 13 through a bore 50, a passage 53 including a spring pressed valve 51 and a bore 54 to the suction conduit 12.

I claim:

In a fuel feeding device for internal combustion engines, the combination with a casing, a pair of interengaging gear wheels within said casing, said casing being provided at opposite

sides of the line of engagement of said gear wheels with suction and pressure chambers and being also provided with delivery passages, driving means for said gear wheels comprising a shaft on which one of said gear wheels is mounted and which is rotatable therewith, and a bushing fitted in said casing and providing a bearing for said shaft, said shaft being substantially equal in di-

ameter at the part carrying the said gear wheel and at the part mounted in said bushing, the part of said shaft mounted in said bushing and the bushing providing a bearing therefor being provided with cooperating distributing passages communicating respectively with said pressure chamber and with said delivery passages. 5

FRIITZ EGERSDÖRFER.
